UNITED STATES PATENT OFFICE.

MARTIN E. EVANS, OF CHEBANSE, ILLINOIS.

DRIVING-CAP.

1,178,143.

Specification of Letters Patent.

Patented Apr. 4, 1916.

Application filed March 22, 1915. Serial No. 16,122.

To all whom it may concern:

Be it known that I, MARTIN E. EVANS, a resident of Chebanse, in the county of Iroquois and State of Illinois, have invented a 5 new and useful Improvement in Driving Caps, of which the following is a specification.

This invention relates to a cap for driving posts, piles, etc., and particularly for driving fence posts or the like which are driven by means of a hand sledge or the like, as distinguished from posts or piles which are driven by a vertically moving and guided hammer. In driving fence posts by means 10 of a hand sledge, the blows are rarely, if ever, delivered squarely onto the upper end of the post, with the result that the top end of the post is deformed, being split and battered up in the case of a wooden post and in the 15 case of a metal post being bent over and rendered unsightly.

The principal object of this invention is to provide a driving cap for such hand driven posts or the like, which is so designed 25 that the force of the blows, even if delivered unevenly, are directed to the central longitudinal axis of the post, in order to prevent mutilating and injuring the top of the post.

30 Further objects of the invention are to provide a driving cap which is strong and of simple construction, economical to manufacture, strong and durable, and which can be readily placed upon the post and taken 35 off again.

The invention comprises a driving cap constructed and arranged as hereinafter described and claimed.

In the accompanying drawings, Figure 1 40 is a vertical sectional view on the central longitudinal plane of the cap, showing the same in position on a post to be driven; Fig. 2 is a bottom plan view of the same; and Fig. 3 is a vertical sectional elevation of a 45 simplified form of driving cap.

The cap illustrated in Figs. 1 to 3 comprises three main parts, namely, a member 1 which is placed upon the top of the post or pile to be driven, a member 2 above and surrounding the same, and a head 3 for receiving the blows of the sledge or hammer.

50 The member 1 as illustrated is formed to fit on the top of a tubular post 4, being provided with a groove 5 for receiving the upper end of the post, with a depending flange 55 outside of such groove to prevent displace-

ment of the member 1 on the post, and with a downwardly projecting guiding portion, in this instance comprising two intersecting webs 6 at right angles to each other, which extend down into the hollow post. For driving solid posts the member 1 will have its lower face substantially flat, so as to rest directly upon the post, but it may even then have the depending outer flange, but this is not necessary. The guiding member 6 is preferably formed of sufficient length to be of material assistance in placing the cap on a tubular post by slipping it into the upper end of said post.

The member 2 has a substantially solid upper portion lying above the member 1, and a downwardly extending tubular portion or sleeve 8 which surrounds the post and forms an additional means for guiding 75 the driving head on the post and holding it against displacement under the recoil incident to the shock of blows. Interposed between the upper portion of member 2 and the member 1 is means which will direct the 80 force of the blow to the central longitudinal axis of the post. This means may be variously constructed. As shown, it comprises a spherical body or ball 9, held in a suitable seat in the lower face of the member 2, this 85 seat being slightly in excess of a semi-sphere and having the lower ends of its wall portions, as at 10, adapted to be bent or peened inwardly slightly below the center of the ball 9, so as to hold said ball 90 against displacement. This ball 9 need not rotate, and ordinarily does not, but if desired it may be permitted to rotate. The ball engages in a cup-shaped socket 11 in the top face of member 1. Consequently, the 95 forces of a blow are directed practically to a point at the central longitudinal axis of the post. The member 9 may take various forms, but a ball or sphere is preferred, as it possesses maximum strength and can be 100 readily formed. This ball preferably will be formed of steel or other metal of high crushing strength.

To permit movement between the member 2 and member 1 so that the member 2 can 105 rock on member 1 when the blows are not squarely delivered, and still to prevent disengagement between members 1 and 2 when the cap is taken from the post, I provide a loose connection between these parts, this 110 connection being by means of lugs on the member 1, shown as heads of tap bolts 12

which project into vertical slots 13 in the opposite faces of the sleeve 8. In assembling the parts the member 1 is first inserted into the sleeve 8 and then the tap 5 bolts 12 are inserted through slots 13. In order to provide simplified means for limiting movement between members 1 and 2, parallel vertical slits may be cut downwardly from slots 13 and the metal therebetween forced inwardly to form ears 12^a, as shown in dotted lines in Fig. 1. This form is easier to make than the slot and bolt engagement but the latter is preferable since it permits the cap to be lifted from the 10 post as a whole.

The top or head of member 2, may, if desired, serve to receive the hammer blows, but preferably the parts will be cushioned and to provide for this the head 3 is used, 15 and interposed between said head and the top of the member 2 is a suitable cushion 20 16 of leather, felt or other material which will deaden the shock of the blow. The head 3 is provided with a depending flange 25 or tubular portion 14 provided with vertical slots 14^a, and is connected to the sleeved member 2 by a transverse bolt passing through said member 2 and having its nut and head 15 engaging the slots 14^a. This 30 connection permits of a slight yielding or rocking motion of the head 3 on the member 2. The cap can be made of any size to fit a post or pile of any diameter and it also can be used with an ordinary pile 35 driver having a guided hammer, but its principal advantage is when driving posts or the like by means of hand implements in which the blows rarely are delivered squarely. The parts of the cap can be 40 formed of cast or wrought iron or steel and can be made of sufficient strength to withstand the shocks of the blows.

Fig. 3 shows a modified and simplified form of driving cap for tubular posts or 45 piles. As shown, this comprises a hollow member 19 having at its upper end a groove 20 to receive the upper end of the post or pile, with a depending flange 21 outside of the same. In the bottom of the hollow member 19 is placed suitable cushioning material 22, of leather, felt, wood or the like, upon which a disk 23 of wood, metal, or the like, is placed, having on its upper face a rounded seat for receiving the rounded lower end 50 24 of the driving plunger 25 which fits loosely in the member 19, so it can rock therein, and which at its upper end is provided with the striking head 26. The striking head 26 is 55 preferably secured to the hollow member 19 by means of chains or the like 27, so that the cap can be lifted from the post as a whole without unduly limiting the rocking motion of the head in any direction. With this form the force of the blows on the head 60 26 will be, even though not squarely deliv-

ered thereon, directed to the central longitudinal axis of the post, as described, the striking member 26 being free to rock sideways in the tubular member 19.

The cap described is capable of many 70 modifications, without departing from the spirit of the invention. It will absolutely prevent the mutilation of the upper end of the post or other article being driven, even when the blows are delivered at one side 75 of the head. Furthermore, there is less liability of driving the post out of a straight vertical line when the blow is delivered at one side of the head, as is the case when the driving caps do not provide for directing 80 the force of the blow to the central vertical axis of the post.

What I claim is:

1. A driving cap for posts and the like, comprising a member arranged to rest on 85 the upper end of the post, a blow-receiving member, and connections between said members arranged to transmit the force of the blows to the central longitudinal axis of the post, said members being guided and held solely by engagement with the post and with each other.

2. A driving cap for posts and the like, comprising a member arranged to rest on 95 the upper end of the post, a blow-receiving member, and a rounded projection on one of said members and contacting with the other of said members in its central vertical axis, said members being guided and held solely by engagement with the post and with 100 each other.

3. A driving cap for posts and the like, comprising a post engaging member, a member resting upon said post engaging member, said members having rocking contact 105 with each other at their central vertical axis, and a buffer member resting on said second member and arranged to receive the blow and transfer the force thereof to said second member.

4. A driving cap for posts and the like, comprising a post engaging member, a sleeved member above and surrounding said post engaging member, said members having a rocking engagement at their central vertical axes only, and a buffer head resting on and secured to said sleeved member.

5. A driving cap for posts and the like, comprising a post engaging member, a sleeved member above and surrounding said post engaging member, a rounded projection on one of said members and contacting with the other of said members at its central vertical axis, and a buffer head resting upon 120 said sleeved member and having a yielding connection therewith.

6. A driving cap for tubular posts and the like, comprising a member provided with a seat to rest on a tubular post and with a downward projection to extend into the 125 130

post, a blow receiving member, and connections between said members arranged to transmit the force of the blows to the central longitudinal axis of the post.

5 7. A driving cap for tubular posts and the like, comprising a member provided with a seat to rest on a tubular post and with a downward projection to extend into the post, a blow receiving member, and a rounded projection on one of said members and contacting with the other of said members in its central vertical axis.

10 8. A driving cap for posts and the like, comprising a post engaging member, blow-receiving member above said post engaging member and provided with a downwardly projecting guiding sleeve, one of said members being provided with vertical slots and the other with projections entering said

20 slots, and connections between said members arranged to transmit the force of the blow to the central longitudinal axis of the post.

25 9. A driving cap for posts and the like, comprising a post engaging member, a sleeved member above said post engaging member and provided with a downwardly extending guiding sleeve embracing the post, one of said members being provided with vertical slots and the other with projections entering said slots, connections between said members arranged to transmit the force of the blow to the central longitudinal axis of the post, and a buffer head resting on and having a yielding connection with said sleeved member.

30 35 10. A driving cap for tubular posts and the like, comprising a member provided with a seat to rest on the tubular post and with a projection to extend into the post, a

blow receiving member, connections between 40 said members for transmitting the force of the blow to the central longitudinal axis of the post, and buffing means associated with said members.

11. A driving cap for tubular posts and 45 the like, comprising a member provided with a seat to rest on a tubular post and with a downward projection to extend into the post, a sleeved member above said post engaging member provided with a downwardly 50 projecting guiding sleeve embracing the post, connections between said post engaging member and said sleeved member arranged to permit relative vertical and rocking movements, and force transmitting connections between said members located in the central vertical axes of said members.

12. A driving cap for tubular posts and the like, comprising a member provided with a seat to rest on a tubular post and 60 with a downward projection to extend into the post, a sleeved member above said post engaging member provided with a downwardly projecting guiding sleeve embracing the post, connections between said post 65 engaging member and said sleeved member arranged to permit relative vertical and rocking movements, force transmitting connections between said members located in the central vertical axes of said members, and 70 buffing means associated with said members.

In testimony whereof, I have hereunto set my hand.

MARTIN E. EVANS.
